CLAIM

We claim the ornamental design for an RFID animal ear tag, as shown.

DESCRIPTION

FIG. 1 is a perspective view of an RFID animal ear tag, in accordance with our new design;

FIG. 2 is a front elevational view of the RFID animal ear tag shown in FIG. 1;

FIG. 3 is a rear elevational view of the RFID animal ear tag shown in FIG. 1;

FIG. 4 is a side elevational view of the RFID animal ear tag, taken from the left side of FIG. 1;

FIG. 5 is a side elevational view of the RFID animal ear tag, taken from the right side of FIG. 1;

FIG. 6 is a top plan view of the RFID animal ear tag shown in FIG. 1; and,

FIG. 7 is a bottom plan view of the RFID animal ear tag shown in FIG. 1.
